CLAIM

The ornamental design for a coffee and espresso maker, as shown and described.

DESCRIPTION

FIG. 1 is a top plan view of a coffee and espresso maker showing our new design;

FIG. 2 is a front elevational view thereof;

FIG. 3 is a left side elevational view thereof; and

FIG. 4 is a right side elevational view thereof.

The back of the coffee and espresso maker is unornamented and the bottom of the coffee and espresso maker is flat and unornamented.

FIG. 1

FIG. 2

FIG. 3

FIG. 4
